(57) **CLAIM**

The ornamental design for a recessed light, as shown and described.

DESCRIPTION

FIG. 1 is a perspective view of a recessed light showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is another perspective view of the recessed light showing my design.

1 Claim, 6 Drawing Sheets

FIG. 1

FIG. 2

FIG.3

FIG. 5

FIG. 4

FIG. 6

FIG. 7

FIG. 8
